UNITED STATES PATENT OFFICE

101,876

DESIGN FOR A LIQUID DISPENSING CONTAINER OR THE LIKE

George J. Lalinsky, Detroit, Mich.

Application August 27, 1936, Serial No. 64,593

Term of patent 14 years

To all whom it may concern:

Be it known that I, George J. Lalinsky, a citizen of the United States, residing at Detroit, county of Wayne, State of Michigan, have invented a new, original, and ornamental Design for a Liquid Dispensing Container or the like, of which the following is a specification, reference being had to the accompanying drawing forming part thereof.

In the drawing:

Figure 1 is a perspective view of the liquid dispensing container or the like, showing my new design, and

I claim:

The ornamental design for a liquid dispensing container or the like as shown.

GEORGE J. LALINSKY.
